US0D1026844S

(12) **United States Design Patent** (10) **Patent No.:** **US D1,026,844 S**
(45) **Date of Patent:** **** May 14, 2024**

(54) **INFRARED THERMOGRAPHY CELLPHONE**

(71) Applicants: **Guangzhou SATIR Technology Co., LTD.**, Guangzhou (CN); **Guangzhou SAT Infrared Technology Co., LTD.**, Guangzhou (CN); **Guangzhou SAT Infrared System Software Co., LTD.**, Guangzhou (CN); **Guangzhou Infrared Technology Co., LTD.**, Guangzhou (CN)

(72) Inventors: **Jiping Wu**, Guangzhou (CN); **Zhenpeng Chen**, Guangzhou (CN); **Ren Tan**, Guangzhou (CN)

(73) Assignees: **Guangzhou SATIR Technology Co., LTD.**, Guangzhou (CN); **Guangzhou SAT Infrared Technology Co., LTD.**, Guangzhou (CN); **Guangzhou SAT Infrared System Software Co., LTD.**, Guangzhou (CN); **Guangzhou Infrared Technology Co., LTD.**, Guangzhou (CN)

(**) Term: **15 Years**

(21) Appl. No.: **29/863,614**

(22) Filed: **Dec. 21, 2022**

(51) LOC (14) Cl. **14-03**

(52) U.S. Cl.

USPC ..... **D14/138 G**

(57) **CLAIM**

The ornamental design for an infrared thermography cellphone, as shown and described.

DESCRIPTION

FIG. 1 is a front perspective view of an infrared thermography cellphone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

1 Claim, 8 Drawing Sheets
